UNITED STATES PATENT OFFICE.

MYRON G. MOLYNEAUX, OF ARIEL, PENNSYLVANIA.

COVER-SUPPORT.

1,119,188.

Specification of Letters Patent.

Patented Dec. 1, 1914.

Application filed November 26, 1913. Serial No. 803,350.

To all whom it may concern:

Be it known that I, MYRON G. MOLYNEAUX, a citizen of the United States, residing at Ariel, in the county of Wayne and State of Pennsylvania, have invented certain new and useful Improvements in Cover-Supports; and I do hereby declare the following to be a full, clear, and exact description of the invention, such as will enable others skilled in the art to which it appertains to make and use the same.

The object of this invention is to provide a supporting and locking device for covers, and is especially adapted for locking the covers over earthenware jars and receptacles for protecting them against the entrance of mice, etc.

A further object is to provide a device of this character which shall be adjustable so as to be equally adaptable to receptacles of various sizes.

In the accompanying drawing wherein is shown an approved embodiment of the invention, Figure 1, represents a front elevation of the adjustable supporting and locking device attached to an ordinary earthen jar. Fig. 2, represents a side elevation thereof. Fig. 3, represents a sectional view on the line 3—3 of Fig. 1.

Referring to the drawing in detail wherein similar reference numerals designate corresponding parts throughout the several views, the numeral 5 indicates the base of the supporting frame for the cover and is preferably formed of a piece of wire having its central portion oppositely looped as at 6, and its outer extremities turned up and looped as at 7. Straps 8, are pivoted at their lower ends over the looped ends 7 of the base, and the upper ends are turned inwardly and apertured. The intermediate portions of the straps 8, are provided with a series of openings 9, for a purpose to be hereinafter more clearly described.

A spring wire member 10, having the lower ends 11 turned outwardly and engaged within the openings 9 and the strap 8, and the adjacent portions looped at 12 to increase the resiliency of the lower ends thereof. The central portion or that portion of the spring member 10 intermediate the loops 12, is provided with an offset portion 13 for receiving the cover supporting and locking member 14.

The cover supporting and locking device member 14, consists of a single piece of sub-

stantially heavy wire bent so as to provide a handle portion 15 and looped portion 16, receiving the offset portion 13 of the member 10 and the angularly directed end 17 carrying a clip 18, fixed to the cover 19.

As shown in the drawing the receptacle 20, is adapted to be positioned over the oppositely directed loops 6 of the base 5, so as to rigidly hold the latter in position thereunder, the outwardly bent ends 11 of the supporting member 10, are then engaged within a pair of openings of the series 9, in the straps 8, whereby when said straps and member 10, are swung to a vertical position as shown in Figs. 1 and 2, the cover 19 will snugly engage upon the upper edge of the receptacle 20, thereby sealing the latter. To lock the cover over the receptacle 20, the handle 15 of the cover supporting and locking member is moved to the position shown in Fig. 2, and to partially raise said cover, said handle is given an upward movement and the cover and member 14 are swung upwardly, in this position the entire upper portion of the cover supporting device may be swung downwardly from the looped ends 7, of the base member and the receptacle 20 removed.

Having thus fully described my invention what I claim as new and desire to secure by Letters-Patent is;

1. In a device of the character described a base member, straps pivoted to said base member, a cover, and means for adjustably, and removably, attaching said cover to said straps.

2. In a device of the character described, a base member having the ends looped upwardly and the intermediate portions oppositely and laterally looped, straps pivoted to the looped ends of said base member, a member connecting said straps and adjustably secured to the latter, and a cover supporting and locking device carried by said last mentioned member.

3. In a device of the character described a base member, straps pivoted to said base member, a cover supporting member, means for adjustably securing said cover supporting member to said straps, and a cover loosely mounted upon said supporting member.

4. In a device of the character described a base member, apertured, straps pivoted to said member, a cover supporting member, means carried by said supporting member,

and co-acting with said apertured straps for adjusting the former, and a cover loosely mounted upon said supporting member.

5. In a device of the character described a base member, apertured straps pivoted thereto, a supporting member, resilient means carried by said supporting members, and co-acting with said apertured straps for adjustably supporting the former and a 10 cover pivotally mounted upon said supporting member.

6. In a device of the character described a base member, apertured straps pivoted to said base member, a cover supporting member, means carried by said supporting member and co-acting with said straps for adjusting the former, a cover and means con-

nected to said cover for swinging the same upon said supporting member.

7. The combination with a cover of a supporting member, locking means carried by said supporting member and attached to said cover, resilient adjusting means carried by said cover supporting member, a base member and pivoted means carried by said 25 base member for co-acting with said resilient means.

In testimony whereof I have signed my name to this specification in the presence of two subscribing witnesses.

MYRON G. MOLYNEAUX.
